(57) **CLAIM**

The ornamental design for an exhaust gas recirculation
cooler, as shown and described.

DESCRIPTION

FIG. 1 is a perspective view of an ornamental design for an
exhaust gas recirculation cooler, showing our new design;

FIG. 2 is a right side view thereof;

FIG. 3 is a left side view thereof;

FIG. 4 is an enlarged rear view thereof;

FIG. 5 is an enlarged front view thereof;

FIG. 6 is a bottom view thereof; and,

FIG. 7 is a top view thereof.

The broken lines in the figure drawings, show unclaimed
environment only and forms no part of the claimed design.
